UNITED STATES PATENT OFFICE.

WILLIS H. SMITH, OF KNOXVILLE, TENNESSEE.

ENGINE VALVE-GEAR.

1,132,692.

Specification of Letters Patent. Patented Mar. 23, 1915.

Application filed July 22, 1914. Serial No. 852,411.

To all whom it may concern:

Be it known that I, WILLIS H. SMITH, citizen of the United States, residing at Knoxville, Tennessee, have invented certain new and useful Improvements in Engine Valve-Gear, of which the following is a specification.

My present invention relates to the type of valve gear disclosed in Letters Patent of the 10 United States granted to me February 10, 1914, #1,086,476. In this type of valve gear the slide valve is operated through connections leading to an auxiliary crank mounted on a main crank which, in turn, is mounted 15 on the drive wheel, and which main crank is connected through a pitman to the ordinary piston rod, the control of the slide valve being effected by connections from a hand lever to the pitman which forms a 20 part of the connection between the auxiliary crank and the said slide valve.

The invention consists in the features of construction and arrangement and combination of parts hereinafter described and particularly defined by the appended claims.

The accompanying drawing shows in side elevation and in the nature of a diagram the improvement in place and connected up with the connections leading to the slide valve.

30 In these drawings, the drive wheel is indicated at 5 provided with a main crank 6 which is connected through a pitman or main rod 7 with the ordinary crosshead 7' from which the ordinary piston rod 7^a extends to the piston in the steam chest or cylinder.

8 indicates an auxiliary crank mounted on the main crank 6 and from which connections lead to the slide valve to operate 40 the latter. These connections include the pitman 9, a link 10 extending upwardly from the end thereof, and connected with an arm 11 fixed on a shaft 12 mounted in a bracket 15, the said shaft 12 also having an 45 arm 13 connected with the rod 14 which leads to the slide valve (not shown) for operating the same. A fulcrum is provided for the pitman 8 near its point of connection with the link 10 so that as the auxiliary 50 crank 8 moved in a concentric path around the axis of the drive wheel 5, a forward and back and a vertically oscillating movement will be given to the pitman 9, and this movement will be imparted through the link 10, 55 arms 11 and 13, and rod 14 to the slide valve.

This fulcrum for the pitman 9 is furnished by a link 31 connected with the pitman 9 pivotally at 30, the upper end of said link 31 being connected at 32 pivotally with a rocker member 23 which, in turn, is supported on rocker arms 20 and 22 respectively mounted on the transverse shafts 18 and 21 journaled in suitable bearings on the frame. The rocker member 23 is pivotally connected with the upper ends of these arms 20 and 22, 60 and these arms extend substantially parallel with each other. The rocker arm may assume various forms, but in the particular construction shown it is in the form of a triangle, and the pivot 32 is at the lowermost point of this triangle so that the link 31 is of the same length as the arms 20 and 22. The arm 20, as before stated, is mounted on the shaft 18, and this shaft has another arm thereon which is connected 65 through a rod 19 with the hand lever 34. This hand lever may be set in various positions, and held by a toothed segment indicated generally at 35. By adjusting this hand lever the arm 20, together with the 70 75 rocker arm or triangle 23, will be adjusted, the arm 22 also having rocking movement for this purpose, and thus the upper pivot 32 of the fulcrum link 31 will be altered in position relative to the connections leading 80 to the slide valve, and consequently the fulcrum 30 for the pitman 9 will be altered in its position, and thus the link 10 and the connections therefrom to the slide valve will be adjusted. By the use of the triangular 85 rocker the pivot 32 is arranged low down in respect to the points of connection between the rocker and the arms 20 and 22, and thus the link 31 can be made of the same length as said arms 20 and 22. This will insure 90 proper reversal of the engine, enabling the slide valve to have the proper length of travel.

On the shaft 18 at about the center thereof a counter balance is arranged which consists 100 of two coil springs 36 and 37 connected with the said shaft 18, so that when the gear is shifted forward or backward this counter balance will relieve the weight of the gear and make it easy to operate.

105 All of the parts are duplicated on the other side of the locomotive, excepting the link 19, and the arm to which it is connected, and the reversing lever 34.

The gear may be applied to a stationary 110

or other engine having only one cylinder, in which case only one set of connections above described will be used.

I claim as my invention:—

- 5 1. A steam engine valve gear comprising a pitman, an auxiliary crank connecting the same with the drive wheel, connections from the said pitman to the slide valve, a link pivotally connected with the pitman and
- 10 furnishing a fulcrum therefor, a pair of arms arranged parallel and pivotally mounted at their lower ends, a rocker member connected with the upper ends of said parallel arms, the said fulcrum link being pivotally connected to said rocker member at a point below the points of connection between said rocker member and the parallel arms, so that lines drawn to connect said three points would form a triangle, said
- 15 fulcrum link being of the same length as the said parallel arms, and means for rocking the parallel arms to adjust the fulcrum link, substantially as described.
- 20 2. In combination in engine valve gear, connections to the slide valve including a pitman, an auxiliary crank to which the pit-

man is connected, a pair of parallel arms pivotally mounted at their lower ends, a substantially triangular shaped rocker pivotally connected to said arms at their upper ends, 30 a fulcrum link extending from the low point of said triangular rocker and pivotally connected with the pitman, and means for operating the parallel arms, substantially as described. 35

3. In combination in an engine valve, connections to the slide valve including a pitman and a link at the end of said pitman, an auxiliary crank for driving the pitman, a pair of parallel arms mounted on the frame 40 pivotally, a rocker connected with the parallel arms, a fulcrum link between the rocker and the pitman, and a counter balance connected with one of the parallel arms, substantially as described. 45

In testimony whereof, I affix my signature in presence of two witnesses.

WILLIS H. SMITH.
